Primary Examiner — Thomas Johannes*Assistant Examiner* — Catherine Posthauer(74) *Attorney, Agent, or Firm* — Husch Blackwell LLP(57) **CLAIM**

The ornamental design for an insulating cup sleeve, as shown and described.

DESCRIPTION

FIG. 1 is a perspective view of an insulating cup sleeve; FIG. 2 is a side elevation view thereof; FIG. 3 is a top plan view thereof; FIG. 4 is a bottom plan view thereof;

FIG. 5 is an exploded perspective view showing the insulating cup sleeve in a usage environment with a cup, forming no part of the claim;

FIG. 6 is a perspective view showing the insulating cup sleeve in an alternate usage environment;

FIG. 7 is a side view thereof;

FIG. 8 is a top view thereof; and,

FIG. 9 is a bottom view thereof.

The broken lines are shown for the purpose of illustrating environmental subject matter and parts of the article that form no part of the claimed design.

1 Claim, 6 Drawing Sheets(56)
